Primary Examiner — Philip S Hyder*Assistant Examiner* — Sydney Buffalow(74) *Attorney, Agent, or Firm* — MacMillian, Sobanski & Todd, LLC(57) **CLAIM**

The ornamental design for a product display, as shown and described.

DESCRIPTION

FIG. 1 is a front perspective view of a product display according to the design;

FIG. 2 is a front elevational view thereof;

FIG. 3 is a right side elevational view thereof, the left side elevational view being a minor image thereof;

FIG. 4 is a back elevational view thereof;

FIG. 5 is a top plan view thereof;

FIG. 6 is a bottom plan view thereof; and,

FIG. 7 is a front perspective view similar to the view of FIG. 1 showing the positioning of products.

The broken lines shown in the figures are for illustrative purposes only and form no part of the claimed design.
